FIG. 3

FIG. 4

FIG. 1 is a front elevational view of the receptacle for the random mixing and display of enclosed inscribed pieces showing my new design;

FIG. 2 is a side elevational view of the receptacle of FIG. 1 taken from a point to the left of the receptacle as viewed in FIG. 1;

FIG. 3 is a top plan view of the receptacle of FIG. 1;

FIG. 4 is a bottom plan view of the receptacle of FIG. 1.

The side elevational view of the receptacle of FIG. 1 taken from a point to the right of such receptacle as viewed in FIG. 1 has not been shown in that it is a mirror image of the side elevational view of FIG. 2.

I claim:

The ornamental design for a receptacle for the random mixing and display of enclosed inscribed pieces, as shown and described.
